[57] CLAIM

The ornamental design for a luminaire, substantially as shown.

DESCRIPTION

FIG. 1 is a pictorial view of a luminaire incorporating my new design.

FIGS. 2 through 7 are, respectively, side, rear, opposite side, front, top and bottom views of the luminaire and taken in the directions indicated by corresponding arrows in FIG. 1.

*FIG. 1.**FIG. 2.**FIG. 3.**FIG. 4.**FIG. 5.**FIG. 6.**FIG. 7.*
